UNITED STATES PATENT OFFICE.

JAMES D. GAILOR, OF AHNAPEE, WISCONSIN.

BIN.

SPECIFICATION forming part of Letters Patent No. 334,652, dated January 19, 1886.

Application filed September 11, 1883. Serial No. 176,819. (No model.)

To all whom it may concern:

Be it known that I, JAMES D. GAILOR, a citizen of the United States, residing at Ahnapee, in the county of Kewaunee and State of Wisconsin, have invented certain new and useful Improvements in Bins; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention aims to supply a bin or chest which will be easy of operation, and is intended especially for grocers' use in handling large quantities of flour, sugar, &c.

It consists in the construction illustrated in the accompanying drawings and hereinafter fully described, and specifically pointed out in the claim.

In the drawings, Figure 1 is an elevation, and Fig. 2 is a vertical section, of my device as constructed for family use; and Fig. 3 is an enlarged sectional view showing a slight modification of the bottom of the bin and its supporting beam.

A designates the framing or casing within which the chest is supported.

In the drawings I have shown a framing composed of two sides, A', and a top, A², bottom A³, and four legs, A⁴. The several parts are made of such a relative size that they will form a neat fit for the chest B. When constructed in this manner, the chest is adapted to private use, the top A² serving as a table or shelf.

When arranged for grocer's use, it will be understood the top A² is the store-counter, and chests B are arranged in a series, side by side, under the same, or put in as movable fixtures, if desired, to suit parties also. The chests are supported upon the bottom A³ of the framing. This bottom or support A³ is provided with two semicircular lugs, A⁵, placed a distance apart equal to the width of the chests. The sides of the chests are extended below the bottom of the same, and are so formed as to rest upon the lugs A⁵. These lugs are placed near the front edge of the support A³, and thereby aid the outward move-

ment of the chests in the operation of the same. The upper edge of the chest is made higher in the front than in the back, and is slightly curved, as shown. The rear edge of the top or counter is provided with a depending stop, A⁶, which limits the backward movement of the chest. The longer edge of the chest is cut away toward each end from the lugs A⁵, as shown, so as to present no square corners 60 to stop the ready tilting of the chests.

When the chests are built for grocers' use and are intended to hold heavy goods, I provide the lugs A⁵ with rollers C, as shown in Fig. 3. These rollers reduce the friction between the parts, and the device will stand much more usage than without them.

The operation of the chest will be readily understood. When it is desired to remove any of the contents of the chest, a pull on the front side of the same will cause it to move forward, as shown in dotted lines, Fig. 2, when the contents may be removed and the chests pushed back. It will be seen that the outward movement of the chest is caused by the engagement of the lugs A⁵ and the lower edges of the chests. The labor involved in sliding drawers in the ordinary manner is all dispensed with, and the goods are kept entirely free from dust. When so desired, the legs A⁴ 80 may be provided with casters. It will be noticed that the lugs A⁵ are formed on the arc of a circle, and that the recess formed in the lower edge of the sides of the bin are made of corresponding shape. Thus in the operation of the chest or bin the latter moves in or around a circle, the center of which is the center from which the arc of the lugs is struck; but as said lugs are relatively fixed the bin in its movement traverses thereover in a curvilinear path. 90

I am aware that bins for grocer's use have been mounted on trucks which run on horizontal platforms in the lower part of the casing, the front edge of the platform being beveled to cause the tilting of the bin when drawn out, 95 and that others have also been made and mounted on rockers or pivotal supports, so that they tilt outward, and that it has been common to mount bins on a transverse rod which fits in recesses cut in the lower edge of the side extensions of the chests or bins, and to extend the sides of the bin below its bot-

tom in a tapering form, and to fit the ends of such sides in supports projected from a platform. In operation my bin differs essentially from any heretofore constructed, as it moves in a curvilinear path about semicircular supports. It will be seen that by such movement the bin moves bodily away from the counter on a curved track, as it were, which causes a more rapid movement of the mouth of the bin than its base, as will be readily understood. By my construction the advantage of a gradual sliding motion and the inclining of the counter is attained.

Having thus described my invention, what I claim, and desire to secure by Letters Patent, is—

The combination, with the framing and the circular or curved supports secured thereto, of a bin having wings extended below its bottom and recessed to fit and slide upon the semicircular supports, whereby in its operation the bin moves bodily inward or outward upon said supports in a curvilinear path, substantially as shown, and for the purposes set forth.

In testimony whereof I affix my signature in presence of two witnesses.

JAMES D. GAILOR.
